MULTICOLOR PRINTING PRESS

Leslie W. Claybeurn, Carlton Clayton Claybourne,
and Paul E. Franzen, Chicago, Ill., assignors to
L. W. Claybourne, Inc., Chicago, Ill., a corpora-
tion of Illinois

Application August 18, 1947, Serial No. 769,174

4 Claims. (Cl. 271—51)

1

The invention relates to multi-color printing presses and more particularly to the impression cylinder and the means for supplying a signature or sheet thereto and removing it therefrom after a plurality of revolutions of said cylinder.

The object of the invention is to provide a sheet feed cylinder and a delivery cylinder arranged in juxtaposition relative to the impression cylinder, all of said cylinders being rotated at the same speed and each equipped with sheet gripping mechanism, said gripping mechanism being so controlled that the impression cylinder makes a plurality of revolutions before a new sheet is delivered to it by the feeding in cylinder and the printed sheet is delivered to the delivery cylinder whereby a plurality of color printings from a plurality of plates movable beneath the impression cylinder and in printing registry therewith are imparted to the sheet. More particularly, according to the invention, the impression cylinder makes five revolutions between the time it receives the sheet to be printed from the feeding in cylinder and its delivery to the delivery cylinder, so that five different colors may be printed on said sheet.

The invention further consists in the several features hereinafter set forth and more particularly defined by claims at the conclusion hereof.

In the drawings:

Fig. 1 is a side elevation view of a multi-color printing press embodying the invention;

Fig. 2 is a detailed vertical sectional view taken on the line 2—2 of Fig. 1;

Fig. 3 is a detailed horizontal sectional view taken on the line 3—3 of Fig. 1;

Fig. 4 is a detailed vertical sectional view taken on the line 4—4 of Fig. 2;

Fig. 5 is a detailed vertical sectional view taken on the line 5—5 of Fig. 2;

Fig. 6 is a detailed vertical sectional view taken on the line 6—6 of Fig. 2;

Fig. 7 is a detailed vertical sectional view taken on the line 7—7 of Fig. 2;

Fig. 8 is a detailed vertical sectional view taken on the line 8—8 of Fig. 2;

Fig. 9 is a vertical sectional view showing the gripper control mechanism for the delivery cylinder in one position;

Fig. 10 is a view similar to Fig. 9 showing the gripper control mechanism for the delivery cylinder in another position;

Fig. 11 is a series of diagrammatic views to illustrate the action of the gripper mechanisms during a complete cycle of the machine.

2

Referring to the drawings, Fig. 1 shows a general layout of the multi-color printing press embodying the invention, said press including a sheet feeding in cylinder 12, an impression cylinder 13, and a delivery cylinder 14, the feed of the sheet to the cylinder 12 not being shown. The plate feed mechanism designated generally by the numeral 15 and more particularly shown and described in a copending application Serial No. 762,960, filed July 23, 1947 (now abandoned), moves the printing plates 16 successively under a series of inkers 17 whose operations are so timed that each plate receives its desired color of ink and is thereafter carried under the impression cylinder 13 to deposit its inked portion on the sheet mounted on said cylinder, the press shown being a five color press and having a sheet receiving compartment 18.

The cylinders 12, 13, and 14 are all driven at the same speed through gearing connections with a motor driven drive shaft 19. As shown in Fig. 4, the shaft 19 carries a gear 20 meshing with an idler gear 21 which is connected through an idler gear 22 with a gear 23 on a shaft 24 carrying the impression cylinder 13, the idler gear 22 being connected by an idler gear 25 to a gear 26 on the shaft 27 carrying the feeding in cylinder 12 whereby the cylinders 12 and 13 are driven at a one to one ratio with the drive shaft 19. The delivery cylinder 14 carries gears 28 meshing with gears 29 on the impression cylinder, so that the cylinder 14 is driven at a one to one ratio with the drive shaft 19. The gear 20 is connected by intermeshing idler gears 30 to a gear 31 on a shaft 32 for driving the plate feed mechanism.

The cylinder 12 carries a sheet gripper mechanism comprising a series of grippers 33 arranged in spaced relation upon an oscillatory shaft 34 (see Figs. 2, 3, and 7) which extends out beyond the cylinder 12 through a plate 40 secured to said cylinder, said grippers being normally urged to a gripping position by a spring 35 acting on a crank arm 36 secured to said shaft. The shaft 34 carries a segmental gear 37 meshing with a segmental gear 38 free to turn on the shaft 27 which gear 38 meshes with one of a pair of idler gears 39 on a shaft 39 journaled in the plate 40, the other gear 39 meshing with a segmental gear 41 rotatably mounted on a shaft 42 carried by said plate, the hub of said gear 41 being connected to a crank arm 43 which carries a roller 44 that works in cam tracks 45 and 46 in a stationary cam 47 mounted on a bracket 47' (see Figs. 2 and 6). The roller is shifted from one cam

track to the other by a finger 48 secured to a shaft 49 pivotally mounted in the cam 47 and carrying a crank arm 50 which is operated by a lengthwise adjustable link 51 operatively connected to an arm 52 of a bell crank lever pivotally mounted on a shaft 53 carried by a fixed bracket 54 and having an arm 55 carrying a roller 56 working in a cam groove 57. The lengthwise adjustment of the link 51 is provided by a yoked end pivot member 58 adapted to be adjustably clamped to one end of said link by nuts 59 engaging the threaded end of said link.

Referring to Figs. 6 and 8, the cam groove 57 is formed in one side of a plate 60 journaled on the shaft 61 carrying the delivery cylinder and cam groove 62 on its opposite side of the same form as the groove 57 but displaced one hundred and eighty degrees relative thereto in which a roller 63 on one arm of a bell crank lever 64 works. The lever 64 is pivotally mounted on a shaft 65 carried by a fixed bracket 66, the other arm of said lever being connected by a pin 67 to a yoke member 68 lengthwise adjustably clamped by nuts 69 to a link rod 70 whose other end is operatively connected by a pin 71 to one arm of a bell crank lever 72 secured to a shaft 73 rotatably mounted in the frame part 74 of the machine and whose other arm is operatively connected by a link 75 with a crank 76 secured to a shaft 77 also rotatably mounted in the frame 74. The shafts 73 and 77 have eccentrically disposed crank pins 78 journaled in the ends of a cam member 79 upon which a roller 80 on an arm 81 secured to an oscillatory gripper shaft 82, mounted on the impression carrying cylinder and spaced grippers 83, rides during a portion of the revolution of the impression cylinder. The roller 80 is yieldingly urged into engagement with the cam 79 by a spring 84 acting on a crank arm 85 secured to shaft 82. The spring 84 acts to hold the grippers 83 engaged with the sheet on the impression cylinder until released by the cam 79 at the end of the fifth revolution of the cylinder 13 and just before the sheet is taken off by the spaced grippers 86 carried by an oscillatory shaft 87 mounted on the delivery cylinder.

Referring to Figs. 6, 9, and 10, the shaft 87 carries a crank arm 88 provided with a roller 89 working on a cam 90 fixed to the machine frame, said roller 89 being yieldingly urged against said cam by a spring 91 acting on a crank 92 secured to the shaft 87. The cam 90 has a portion 93 which holds the grippers 86 in open position and a portion 94 which permits the spring 91 to move the shaft 87 to close the grippers. Also associated with the cam 90 is a lever or shiftable cam extension for said cam 90 whose side 96 forms a cam surface which at certain times acts as a continuation of the portion 93, said lever being mounted on a shaft 97 journaled in the cam 90 and carrying a crank arm 98 which is operatively connected to the link rod 70 by an adjustable link rod 99.

In each instance the gripper closing springs above referred to surround a pair of telescoping rods 100 and 101, most clearly shown in Figs. 8 to 10 inclusive.

The cam member 60 is rotated at a ratio of one to five relative to the cylinders 12, 13 and 14, said cam having a large gear 102 secured thereto which meshes with a small gear 103 on a stud shaft 104 secured to the frame of the machine, said gear 103 being integral with a gear 105 which is driven through gearing connections with the shaft 61 of the delivery cylinder, as shown in

Fig. 3, comprising a transmission shaft 106 carrying at one end a gear 107 meshing with the gear 105 and at the other end a gear 108 meshing with a gear 109 on the shaft 61. Parts of the one to five ratio gearing above described are also shown in Figs. 4 and 5.

From the above description it will be noted that each of the cylinders 12, 13 and 14 is provided with gripper mechanism respectively operated by relatively fixed cams for the cylinders 12 and 14 and a laterally movable cam for the cylinder 13 and that the shifting of the lever 50 controlling cam track shifter finger 48 for the feeding in cylinder 12, the shifting of the cam 79 for the impression cylinder 13, and the shifting of the cam member 60 which makes one revolution to five revolutions of the cylinders 12, 13, and 14 and carries the cams 57 and 62, the cam 57 controlling the finger 48 and the cam 62 controlling the cam 79 and the cam extension 96.

Referring now to Figs. 6 to 10 and 11, the cylinder 12 makes four and one-half revolutions while the roller 44 is moving in the cam track 46 and the finger 48 is in the dotted line position shown in Fig. 6, then the cam 57 acts through the lever 52, link 41 and arm 50 to swing the finger 48 to its full line position, so that the roller 44 is shifted to the outer cam track 45, and while said cylinder is making about a one-half revolution, the grippers 33 are engaging the sheet S and carrying it from the position shown at A to the position B where said grippers 33 are released. The cam 79 is in the outer position for about one revolution to engage the roller 80 and move it with the lever 81 and shaft 82 against the pressure of the spring 84 to swing the grippers 83 to an open position to receive the sheet S when released by the grippers 33 on the feeding in cylinder. As the roller 80 drops off the cam 79, said cam is retracted by motion imparted from the cam groove 62, lever 64, links 68 and 70, levers 72 and 76, and parallel link 75 to turn the pins or crank members 78, thus permitting the grippers 83 to close on the sheet to carry it around on the impression cylinder as shown in views C and D. The movement of the cam 79 outwardly to a gripper release position takes place on the fourth revolution of the impression cylinder just after the gripper roller 80 has passed the trailing edge of the cam 79 which then remains in its outward position until on the fifth revolution said roller 80 has passed over it after which it is retracted. During the fifth revolution with the grippers 83 released the grippers 86 of the delivery cylinder on the retraction of the cam surface 96 are permitted to engage the forward end of the sheet as shown in view E and carry it onto the delivery cylinder as shown in view F from which it is removed by the delivery mechanism, not shown. The cam 79 must be in the outer position before the roller 80 engages it to release the sheet S, so that it may be transferred to the delivery cylinder 14 by the grippers 86. During the fifth revolution of the impression cylinder while the transfer of the printed sheet is taking place, a new sheet S is picked up by the feed in cylinder as shown in view E, and as the cam 79 is again moved inwardly, the grippers 83 close on this sheet, as shown in view F, to transfer it from said feed in cylinder 12 to the impression cylinder 13.

Thus while all the cylinders 12, 13, and 14 rotate at the same speed, the impression cylinder makes five revolutions to permit the printing

of five colors on the same sheet by the printing plates 16 before this sheet is removed by the gripper mechanism of the delivery cylinder and a new sheet is received from the feeding in cylinder.

It will be noted that the gripper mechanism for the impression cylinder 13 is closed at all times except when the cam 79 is moved radially outwardly to contact the roller 80 so as to open the grippers 83 to receive the sheet, as shown in views B, C, and F, and release it as shown in view E, and that grippers 86 of the delivery cylinder close every time this cylinder revolves but close past the point of take off for four revolutions relative to the cam 90 but that on the fifth revolution the lever cam 95 is swung inwardly as shown in Fig. 9, so that the grippers will close on the sheet as shown in view E to take it off of the impression cylinder.

It is to be noted that the cam 79 when moved radially outwardly opens the gripper mechanism of the impression cylinder to permit transfer of the printed sheet to the delivery cylinder as shown in view E and keeps the grippers open until said impression cylinder moves to a position to receive a new sheet from the feeding in cylinder as shown in view F.

We desire it to be understood that this invention is not to be limited to any particular form or arrangement of parts except in so far as such limitations are included in the claims.

What we claim as our invention is:

1. In a multi-color printing press, the combination of an impression cylinder, a feeding in cylinder and a delivery cylinder arranged in juxtaposition, means for rotating all of said cylinders at the same speed, releaseable sheet gripping mechanism for each of said cylinders, fixed cams for controlling the opening and closing of said gripper mechanisms for said feeding in cylinder and said delivery cylinder, a movable cam for controlling the opening and closing of the gripper mechanism of the impression cylinder, a rotatable cam member, means for rotating said cam member at a slower speed than said cylinders so that said cylinders make a plurality of revolutions to one revolution of said cam member, a shiftable member associated with the fixed cam for the feeding in cylinder, a shiftable cam member associated with the fixed cam for said delivery cylinder, and means operatively connecting said cam member with said shiftable member, said shiftable cam member, and said movable cam whereby the sheet to be printed is received by the impression cylinder from the feeding in cylinder and carried upon said impression cylinder for a plurality of revolutions to permit printing of a plurality of colors thereon before being removed by the gripper mechanism of the delivery cylinder.

2. In a multi-color printing press, the combination of an impression cylinder, a feeding in cylinder and a delivery cylinder arranged in juxtaposition, means for rotating all of said cylinders at the same speed, releaseable sheet gripping mechanism for each of said cylinders, a fixed double track cam for controlling the opening and closing of the gripper mechanism for the feeding in cylinder, a shiftable member for determining which cam track is effective to control said gripper mechanism, a rotatable cam member, means for rotating said cam member at a slower speed than said cylinders so that said cylinders make a plurality of revolutions to one revolution of said cam member, means operatively connect-

ing said cam member with said shiftable cam member to time its operation, and means for controlling the gripper mechanisms of said impression and delivery cylinders in cyclic synchronism with that of said feeding cylinder whereby the sheet to be printed is received by the impression cylinder from the feeding in cylinder and carried upon said cylinder for a plurality of revolutions to permit printing of a plurality of colors thereon before being removed by the gripper mechanism of the delivery cylinder.

3. In a multi-color printing press, the combination of an impression cylinder, a feeding in cylinder and a delivery cylinder arranged in juxtaposition, means for rotating all of said cylinders at the same speed, releaseable sheet gripping mechanism for each of said cylinders, a fixed double track cam for controlling the opening and closing of the gripper mechanism for the feeding in cylinder, a shiftable finger for determining which cam track is effective to control said gripper mechanism, a rotatable cam member, means for rotating said cam member at a slower speed than said cylinders so that said cylinders make a plurality of revolutions to one of said cam members, a movable cam for controlling the gripper mechanism for the impression cylinder, a fixed cam for controlling the opening and closing of the gripper mechanism of the delivery cylinder, a shiftable cam member associated with said last named fixed cam to open the gripper mechanism of said delivery cylinder for effecting the transfer of the printed sheet from the impression cylinder to the delivery cylinder, and means operatively connecting said rotatable cam member with said finger, said movable cam, and said shiftable cam member whereby the sheet to be printed is received by the impression cylinder from the feeding in cylinder and carried upon said impression cylinder for a plurality of revolutions to permit printing of a plurality of colors thereon before being removed by the gripper mechanism of the delivery cylinder.

4. In a multi-color printing press, the combination of an impression cylinder, a feeding in cylinder, and a delivery cylinder arranged in juxtaposition, means for rotating all of said cylinders at the same speed, releaseable sheet gripping mechanism for each of said cylinders, a fixed double track cam for controlling the opening and closing of the gripper mechanism for the feeding in cylinder, a shiftable finger for determining which cam track is effective to control said gripper mechanism, a movable cam member for controlling the gripper mechanism for the impression cylinder, a fixed cam for controlling the opening and closing of the gripper mechanism of the delivery cylinder, a shiftable cam member associated with said last named fixed cam to open the gripper mechanism of said delivery cylinder for effecting the transfer of the printed sheet from the impression cylinder to the delivery cylinder, a pair of oppositely disposed cams, means for rotating said cams at a slower speed than said cylinders so that said cylinders make a plurality of revolutions to one revolution of said cams, means operatively connecting one of said pair of cams to said finger to operate the same, and means for operatively connecting the other of said pair of cams to said movable cam member for the impression cylinder and said shiftable cam member for the delivery cylinder to operate the same whereby the sheet to be printed is received by the impression cylinder from the feeding in cylinder and carried upon said impression

cylinder for a plurality of revolutions to permit printing of a plurality of colors thereon before being removed by the gripper mechanism of the delivery cylinder.
